UNITED STATES PATENT OFFICE.

LAVINIA S. WEBER, OF PHILADELPHIA, PENNSYLVANIA.

DESIGN FOR A KNIFE-SCOURER.

SPECIFICATION forming part of Design No. 25,063, dated January 21, 1896.

Application filed November 14, 1895. Serial No. 568,974. Term of patent 7 years.

To all whom it may concern:

Be it known that I, LAVINIA S. WEBER, a citizen of the United States, residing in the city and county of Philadelphia, State of Pennsylvania, have invented and produced a new and original Design for a Knife-Scourer, of which the following is a specification, reference being had to the accompanying drawings, forming part thereof.

The leading feature of my design for a knife-scourer is a knife-scourer having a base, a bulbous head rising thereon and cross-bars projecting in opposite directions from the sides of said head.

Figure 1 represents a perspective view of a knife-scourer embodying my design. Fig. 2 represents a top or plan view thereof.

Similar letters of reference indicate corresponding parts in the two figures.

In the drawings, A designates a knife-scourer, consisting of the base B, the bottom pad C therein, the head D on said socket, and the cross-bars E, which latter project in opposite directions from the sides F of said head.

The head D is somewhat spherical or bulbous, the sides F thereof being flattened.

What I claim is—

The design for a knife scourer, substantially as described and shown.

LAVINIA S. WEBER.
